[57] **CLAIM**

The ornamental design for a vase, as shown and described.

DESCRIPTION

FIG. 1 is a front elevational view of a vase showing our new design, a flower being shown in phantom for illustrative purposes only and forming no part of the claimed design;

FIG. 2 is a rear elevational view thereof;

FIG. 3 is a left side elevational view thereof, a flower being shown in phantom for illustrative purposes only and forming no part of the claimed design;

FIG. 4 is a right side elevational view thereof;

FIG. 5 is a top plan view thereof; and

FIG. 6 is a bottom plan view thereof.
